2 SHEETS—SHEET 2.

UNITED STATES PATENT OFFICE.

HENRY A. SCHaub AND FRED S. CRAWFORD, OF HUNTINGTON, WEST VIRGINIA.

BARREL HOIST AND RACK.

1,223,295.

Specification of Letters Patent. Patented Apr. 17, 1917.

Application filed March 28, 1916. Serial No. 87,252.

To all whom it may concern:

Be it known that we, HENRY A. SCHaub and FRED S. CRAWFORD, citizens of the United States, residing at Huntington, in 5 the county of Cabell and State of West Virginia, have invented a new and useful Barrel Hoist and Rack, of which the following is a specification.

The device forming the subject matter of 10 this application is adapted to hold in horizontal position, a barrel or like object, and the invention aims to provide a structure of this sort including a three-point barrel support and a three-point tripod, the foregoing 15 construction being brought about by the use of three principal parts only. The invention aims, further, to provide a device of the type above mentioned which may be fashioned simply and with a minimum expenditure of material.

A further object of the invention is to provide a device of this sort which will possess unusual strength.

Changes properly falling within the scope 25 of what is claimed may be made without departing from the spirit of the invention.

In the accompanying drawings:—

Figure 1 is a side elevation of a barrel rack embodying the present invention;

Fig. 2 is a top plan thereof;

Fig. 3 is a front elevation of the rack;

Figs. 4 and 5 are elevations wherein the side member is viewed at right angles;

Fig. 6 is an elevation showing a modified 35 form of intermediate bar.

In carrying out the present invention there is provided an inclined intermediate bar 1 including angularly disposed parts 2 and 3. The bar 1 is equipped along its upper and 40 lower edges with oppositely projecting outstanding flanges 4. The part 2 of the bar 1 terminates in a chine hook 5. At the end of the part 3 of the bar 1 there is fashioned a socket 6. A yoke is provided, the same including side arms 8, a top plate 10, and a spindle 7 projecting upwardly from the top plate, the spindle being held for rotation in the socket 6. The lower end of the socket 6 is broadened as shown at 11 to coöperate 45 with the top plate 10. Mounted in the arms 8 of the yoke is an axle 12 supporting a wheel 9 for rotation.

The invention comprises a pair of Y-shaped side members 14 each including a shank 15, an upstanding arm 16 and a depending arm 17. The arms 16 and 17 each

include a body 18 and a rectangularly disposed reinforcing flange 19, the flanges 19 merging together as shown at 20 to form the shank, and the body portions of the arms 30 being continued onto the shank as clearly shown in Fig. 5. Formed integrally with the extremities of the shanks 15 are foot plates 21. The Y-shaped side members are disposed on opposite sides of the intermediate bar 1, the foot plates 21 being received between the flanges 4, as shown best in Fig. 1, in order that the relative angular relation of the parts may be maintained, as shown in Fig. 1. In the foot plates 21 are formed 35 openings 22 through which extend securing elements 23 uniting the Y-shaped side members with the bar 1 intermediate the ends of the bar. As shown at 50, the depending arms 17 of the side members terminate in 75 legs, receiving axles 51 on which are mounted ground wheels 52, coacting with the wheel 9 to form a tripod.

In practical operation, the barrel B is 40 upended and the chine hook 6 is engaged with 80 one of the chines of the barrel, the barrel subsequently being swung up into the horizontal position of Fig. 1, under which circumstances, the upper end of the intermediate bar 1 and the upstanding arms 16 form 85 a three-point support for the barrel.

In Fig. 6 of the drawings, a slight modification is shown. The intermediate bar is denoted by the numeral 24 and is provided with flanges 25 corresponding to the flanges 4. The chine hook appears at 26. The lower end 27 of the bar 24 is beveled off to co-operate with the floor, the wheel 9 being omitted. The yoke and the wheel 9 constitute to all intents and purposes a part 90 of the bar 1, and either form of the invention may be described properly as comprising an intermediate bar, the lower end of which constitutes a part of the supporting 95 tripod, whether such end be represented by 100 the wheel 9, or be of the form indicated at 27 in Fig. 6.

The device forming the subject matter of this application is of few parts and is simple in construction, maximum strength and 105 rigidity being secured at the expenditure of a minimum amount of material.

Having thus described the invention what is claimed as new is:—

1. A barrel stand comprising an inclined 110 intermediate bar having upper and lower lateral flanges; a pair of Y-shaped side mem-

bers each including a shank, an upstanding arm and a depending arm, the ends of the shanks being provided with foot plates received between the flanges of the intermediate bar; and means for connecting the foot plates with the intermediate bar; the upstanding arms coacting with the upper end of the intermediate bar to form a three-point barrel support, and the depending arms coacting with the lower end of the intermediate bar to form a tripod.

2. A barrel stand comprising a pair of opposed Y-shaped members, each including a shank, an upstanding arm and a depending arm, the arms each comprising a body and an outstanding flange, the flanges merging to form the shank, and the bodies being prolonged onto the upper and lower edges of the shank, the shanks terminating in

transverse foot plates; an inclined intermediate bar including flanges between which the foot plates are received, to dispose the Y-shaped members on opposite sides of the bar; and securing means uniting the foot plates with the bar; the upstanding arms coacting with the upper end of the intermediate bar to form a three-point barrel support, the depending arms coacting with the lower end of the intermediate bar to form a tripod.

In testimony that we claim the foregoing as our own, we have hereto affixed our signatures in the presence of two witnesses.

H. A. SCHaub.
F. S. CRAWFORD.
